(57) **CLAIM**

I claim the ornamental design for a kneepad with a crossed foot strap, substantially as shown and described.

DESCRIPTION

FIG. 1 is a rear elevational view of a kneepad with a crossed foot strap as worn on a user in accordance with the present design;

FIG. 2 is a close up right side elevational view of the bottom portion of the crossed foot strap of FIG. 1 around a user's foot;

FIG. 3 is a front elevational view of a pair of kneepads with crossed foot straps as shown in FIG. 1 as worn on a user; FIG. 4 is a right side elevational view of the lower portion of the kneepad with a crossed foot strap of FIG. 1 as worn on a user in which the upper portion of an upper strap is not shown for ease of illustration;

FIG. 5 is a bottom view of the kneepad with a crossed foot strap of FIG. 1 as worn on a user; and,

FIG. 6 is a top view of the kneepad with a crossed foot strap of FIG. 1 as worn on a user in which the upper portion of an upper strap is not shown for ease of illustration.

Left side elevational views are not shown because they are mirror images of the right side elevational views shown in FIGS. 2 and 4.

The broken lines showing the user's legs and clothing, the means for adjusting the length of the straps, and the attachment means connecting the straps to the waistband and kneepads represent environmental subject matter which forms no part of the claimed design.
